MATERIAL HANDLING APPARATUS

Albert Henderson, Edgewood, Pa., assignor to
William P. Witherow, Pittsburgh, Pa.

Application July 20, 1938, Serial No. 220,253

7 Claims. (Cl. 214—65.2)

This invention relates to apparatus for handling materials and, in particular, to apparatus for loading material on a vehicle for transport, and unloading it therefrom.

The usual method of loading materials on a vehicle and unloading them therefrom by hand is very inefficient since it involves the double handling of each piece or package. Such handling is injurious to certain classes of material. Concrete blocks, for example, hollow tile and the like, are subject to chipping and breakage by careless handling. A more serious objection to the loading and unloading of articles or packages by hand, however, is the time and manual effort required. The vehicle is idle during loading and unloading periods so it is desirable to reduce them to a minimum. Conversely, however, the workmen who load the vehicle are idle while the latter is making its trip unless there are other vehicles to be loaded.

I have invented a mechanism for loading and unloading vehicles in a relatively short time, and with a minimum of manual labor. In a preferred form of the invention, a vehicle such as a motor truck is provided with suitable supports for a travelling hoist. Telescoping beams on the supports carry a trolley beam. The telescoping beams are extensible in one direction and the trolley beam in a direction at right angles thereto. A hoist movable along the trolley beam thus permits a load to be placed on the vehicle body or removed therefrom in a very efficient manner.

My invention also contemplates a novel form of lift for stacked articles such as concrete blocks having spaced voids therein with transverse webs. The lift comprises tong like members adapted to be inserted through the voids in stacked blocks and means for contracting the tongs whereby to raise a plurality of blocks simultaneously. The following detailed description of the invention refers to the accompanying drawings illustrating a present preferred embodiment thereof.

In the drawings:

- Fig. 1 is a side elevation of a vehicle having the invention applied thereto;
- Fig. 2 is a plan view of the lift;
- Fig. 3 is a sectional view taken along the line III—III of Fig. 2;
- Fig. 4 is a sectional view taken along the line IV—IV of Fig. 3;
- Fig. 5 is a partial perspective view showing a detail;
- Fig. 6 is a sectional view taken along the line VI—VI of Fig. 1;
- Fig. 7 is a sectional view taken along a vertical

plane extending longitudinally of the vehicle and on the near side of the trolley beam;

Fig. 8 is a partial plan view illustrating the operation of the telescoping beams and the trolley beam; and

Fig. 9 is a perspective view showing a preferred method of stacking concrete blocks after molding and curing, prior to aging and delivery to the point of use.

Referring now in detail to the drawings, a vehicle 10 such as a motor truck, has a bed 11 adapted to receive the load. Posts or columns 12, which may conveniently be tubular in form, extend upwardly from each corner of the bed 11, being positioned in sockets 13 secured thereto. The posts may be adjusted vertically by means of pins 17 and holes 18. Downward extensions 14 are slidably received in the posts 12 and have screw jacks 15 threaded therein provided with suitable ground engaging feet 16. The extensions 14 are secured in adjusted position in the posts 12 by pins 17' cooperating with spaced holes 18' in the extensions 14 and posts themselves. The former may be tubular as are the posts 12.

Cross rails 19 and 20 (see Figs. 1, 7 and 8) are supported on the posts 12, being carried on brackets 21 and 22. As shown in Fig. 1, the cross rails are preferably built up by welding angles 23 to a plate 24. Rollers 25 journaled in suitable bearings in the angles and plates and spaced along the length of the cross beams, support a telescoping member such as a channel 26 for movement longitudinally along the cross beam.

A trolley beam 27 (see Fig. 6) is composed of an I-beam 28 having plates 29 disposed parallel to its web and welded to its flanges. Rollers 30 journaled in suitable bearings in the plates 29 and the web of the I-beam support extensible members in the form of channels 31 for movement longitudinally of the beam 28. A trolley carriage 32 is movable along the channels 31 on rollers 33 and is provided with a chain block hoist 34. The channels 31 are preferably tied together at the rear end of the I-beam 28.

Channels 35 extend across plates 36 overlying opposite ends of the beam 28. The channels 35 provide bearings for shafts 37. Wheels 38 on the shafts 37 travel along the lower flanges of the channels 26 whereby the trolley beam 27 may be shifted laterally by bodily sidewise movement.

It will be understood from the description already given that the trolley beam 27 may be moved to points beyond opposite sides of the vehicle. Suitable stops confine the wheels 38 within the channels 26. Similar stops prevent

movement of the channels 49 out of the cross rails beyond a predetermined distance. The trolley carriage is similarly confined between the ends of the channels 31 but the latter are permitted to move rearwardly along the beam 28 to limiting position in which a suitable fraction, say one-third, of the length of the channels 31 remains within the flanges of the beam 28. By this arrangement, the invention makes it possible to pick up a load from either side of the vehicle or the rear thereof and deposit it on the bed or vice versa.

In my copending application, Serial No. 62,965 filed February 8, 1936, now Patent No. 2,131,474, granted Sept. 27, 1938, for Method and apparatus 15 for making concrete articles, I have disclosed a method of making concrete blocks according to which the blocks are deposited on skips or carriers for aging. The nominal dimensions of these blocks are usually 8 x 8 x 16 or 8 x 12 x 16. Fig. 9 shows 20 one of the skips at 40, in the process of being loaded with blocks. A skip four feet wide will accommodate four rows of the larger size blocks or six rows of the smaller size. The skips are preferably of such length, e. g., seven feet, as to accommodate a convenient number of blocks lengthwise without exceeding the width of the usual vehicle bed. Eyes 41 at the corners of the skips 40 permit them to be lifted by the hoist 34, with the aid 25 of slings or the like. It will be apparent that 30 loaded skips such as that shown at 40' in Fig. 1 can readily be picked up from either side or the rear of the truck 10 and deposited on the bed thereof.

Figs. 1 to 5 illustrate a lift for removing stacked 35 blocks from the skips en masse, without the necessity of individually handling each block. This mechanism comprises a central longitudinal I-beam 45 provided with a U-bolt 46 adapted to receive the hook of the hoist 34. Angles 47 and 40 plates 48 extend transversely of the I-beam at opposite ends thereof. Channels 49 are disposed on the beams formed by the angles 47 and the plates 48 in spaced apart relation and parallel to the beam 45. Gripper bars 50 depend in pairs from 45 the channels 49 and pivoted thereon at 51. The bars 50 are ribbed as at 52 to increase their rigidity and shaped at their lower ends as indicated at 53 to cooperate with the flaring upper edge 54 of the transverse web 55 dividing the voids 56 50 usually provided in a concrete block. The flared upper edge 54 serves as a hand hold for the convenience of the workmen in placing the block in a wall.

The pairs of bars 50 and the channels 49 are so 55 spaced that when the lift is lowered into a stack of blocks, one gripper bar of each pair descends through the aligned voids on each side of the transverse webs of each individual stack of blocks. The bars 50 and channels 49 are adjustable as to 60 spacing apart so that 12" or 8" blocks can be handled, the 8" blocks requiring two additional channels 49 with tongs. Also the tongs may be made adjustable up and down so that one layer, two layers or three layers of blocks may be 65 handled. In some cases the skip will not be carried by truck as the block tongs can deposit them from storage onto the truck.

Angles 57 extending transversely of the I-beam 45 and secured thereto as by rivets 58 engage the 70 right hand bar 50 of each pair. A screw shaft 59 extends loosely through the vertical legs of the angles 57. Angles 60 disposed adjacent the left hand bars 50 of the several pairs, as shown in Fig. 3 have threaded holes in them adapted to receive the shaft 59. A crank 61 is secured to one

end of the shaft 59. By turning the crank 61, the angles 60 can be caused to approach or recede from the angles 57, thus causing the bars 50 to grip or release the transverse web of the bottom block in each stack. Guide rods 59a extend through the angle bars to maintain the movable angles parallel to the fixed angles at all times.

When the truck has been loaded, as already explained, and driven to the point where the blocks are to be used, the lift is lowered so that the bars 50 descend through the voids of the stacked blocks. The bars 50 must obviously be in their open position when being inserted into the voids. Springs 62 between the bars on the guide rods 59a insure full opening thereof when the shaft 59 has been unscrewed.

When the bars 50 have been inserted, they may be contracted by turning the crank 61 as previously explained. The entire mass of blocks may now be lifted by the hoist 34 and deposited at 20 the desired point. When this has been accomplished, unscrewing the shaft 59 releases the gripper bars so that the lift can be used on the next skip load of blocks.

In delivering materials to a building site, it 25 often happens that the truck must be stopped for unloading on unlevel ground. The extensions 14 and screw jacks 15 permit the cross rails and trolley beams 11 of the truck to be level either independently of or simultaneously with the truck frame, to facilitate unloading at points where the ground is not level. If both the pins 17 and 17' associated with each post 12 remain 30 in place, the truck frame is tilted, as shown in Fig. 1, when the load is leveled by the screw jacks. If it is desired to level the cross rails and trolley beam independently of the body, the upper pin 17 which locks the posts 12 in the sockets 13 may be removed. The lower pins 17' fix the extensions 14 relative to the posts 12 which may 35 then be raised or lowered as may be necessary to level without raising the truck bodily. This feature also permits lowering of the posts 12 during transport to reduce the required overhead clearance. After loading the truck, for example, the 40 jack screws may be employed to lower the posts 12 so that their bottom ends depend below the bed 11. When the point of delivery is reached, of course, the posts 12 should be raised to their full 45 height to provide sufficient clearance for lifting the blocks and moving them laterally or rearwardly of the truck body.

The extensions 14 and screw jacks 15 serve not 50 only to level the load but also act as outriggers, lending increased stability to the body and limiting the likelihood of overturning on picking up or discharging a load of blocks.

The advantages of the invention reside particularly in the saving of time and labor required for 55 loading and unloading operations. This time saving means that the truck is actually operating for a greater portion of the time than in the case of hand loading. A further advantage is the reduction in chipping, breakage and the like, a large 60 part of which is the result of manual handling piece by piece. The invention may be used for handling articles other than blocks. Piles of lumber, cement sacks or the like may easily be handled by means of slings. The ability to load or 65 unload a truck from either side or the rear is a 70 distinct advantage because frequently the truck driver has little or no choice as to how he shall approach the point of delivery, while the load must usually be placed in a particular spot on the job.

Although I have illustrated and described but a preferred embodiment of the invention, it will be understood that changes therein may be made without departing from the spirit thereof or the scope of the appended claims. The hoisting frame may be operated by the truck engine if desired.

5 I claim:

1. Loading and unloading mechanism for a vehicle comprising supporting members extending upwardly from the vehicle frame, cross rails carried on said members, a trolley beam movable laterally on said rails, said rails and beam being extensible laterally and longitudinally, respectively, and a hoist movable along said beam.

10 2. Material handling mechanism adapted to be mounted on a vehicle body comprising a trolley beam, telescoping end beams transverse to the trolley beam, wheels mounted adjacent the ends of the trolley beam adapted to travel along said end beams, an extensible member movable along said trolley beam, and a hoist adapted to travel along said member.

15 3. Material handling mechanism adapted to be mounted on a vehicle body comprising a trolley beam extending longitudinally of the vehicle, means including telescoping beams supporting said trolley beam for bodily movement sidewise to points beyond the sides of the vehicle, said trolley

beam mounting an extensible member movable therealong to the rear of the vehicle, and a hoist movable along said member.

4. Loading and unloading mechanism for a vehicle comprising columns adjacent the corners of the load-supporting surface of the vehicle, lateral telescoping beams mounted on said supports, a telescoping trolley beam traveling on said lateral beams, and jacks on said columns, extending downwardly therefrom and adapted to engage the ground for leveling the vehicle.

5 5. Loading and unloading mechanism for a vehicle as defined by claim 4 and characterized by said jacks being adjustably secured to said columns.

10 6. Loading and unloading mechanism for a vehicle as defined by claim 4 and characterized by said columns being tubular and said jacks being slidably received in the lower ends thereof.

15 7. Material handling apparatus comprising two pairs of columns, a cross rail connecting the columns of each pair, a traveling beam movable longitudinally of each rail, a trolley beam having wheels adjacent the ends thereof traveling on said rails, an extensible member movable longitudinally of said beam, and a carriage traveling on said member.

20 25 ALBERT HENDERSON.
